POWER UNIT FOR WASHING MACHINES

John Mikulasek, Newton, Iowa, assignor to The
Maytag Company, Newton, Iowa, a corporation
of Delaware

Application August 6, 1936, Serial No. 94,557

7 Claims. (Cl. 74—75)

The present invention relates to washing machines and more particularly to a novel power unit and means and mechanism for operating the agitator or impeller of a washing machine.

Among the objects of the present invention is to provide a novel means and mechanism for operating the agitator or impeller of a washing machine so as to give it rapid oscillatory or reciprocatory movements and thereby vigorously impelling the washing fluid and garments or clothes carried by the fluid in suspension, in substantial gyratory or circuitous paths.

A further object is to provide a novel power unit for a washing machine of the gyrator or impeller type, in which the gyrator or impeller is oscillated through a desired arc or stroke with a rapidly accelerated and decelerated motion so as to produce greater turbulence of the washing fluid than is now produced in washing machines of this type in general use. This greater turbulence of the washing fluid produces a greater and faster turnover and washing of the garments carried in the fluid.

Another object of the present invention is to provide a novel power unit with means for adjusting and varying the stroke or arc through which the agitator or impeller is oscillated.

Another object is to provide a novel power unit with means for adjusting the stroke of a washing machine agitator or impeller, whereby to vary the rate of acceleration and deceleration of the agitator or impeller during its stroke or path of travel.

A still further object is to provide a novel means and mechanism for driving the agitator and wringer shafts of a washing machine.

Another object of the present invention is to provide a novel means for housing the agitator and wringer drive mechanism in a washing machine. In its preferred form the drive mechanism is encased or enclosed in two small housings spaced apart but operatively connected together.

A further object is to provide novel clutch mechanism for clutching and declutching the agitator or impeller shaft with the power drive.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawings, and while I have shown therein a preferred embodiment,

it is to be understood that the same is susceptible of modification and change, and comprehends other details, arrangements of parts, features and constructions without departing from the spirit of the invention.

5

In the drawings:

Fig. 1 is a view in side elevation of a washing machine equipped with the novel drive mechanism.

Fig. 2 is a plan view of the novel drive mechanism, the tub being shown in dotted outline.

Fig. 3 is a view, part in side elevation and part in vertical cross section, through the novel drive unit.

Fig. 4 is a fragmentary view in vertical cross section of an alternate construction of oscillating drive and clutch arrangement.

Fig. 5 is a plan view of the link drive shown in Fig. 2, but disclosed in another position of its travel.

Fig. 6 is a fragmentary view in front elevation and

20

Fig. 7 is a fragmentary view, part in side elevation and part in vertical cross section, of the drain.

25

Referring more particularly to the drawings, the novel power unit is shown as embodied in a washing machine 1 having a tub 2 in which is mounted an agitator or impeller 3 of the gyrator type. The agitator is rotatably mounted upon a drive shaft 4 extending through the bottom of the tub with the lower end rotatable in the step-bearings 5 in the boss 6 of the gear casing 7. This casing forms a housing for the power unit or drive mechanism adapted to be driven by a motor, engine or other power plant 8, through the medium of a pulley 9 driving by means of a belt or the like 10, a pulley 11 mounted upon the drive shaft 12.

The drive shaft 12 rotates in bearings 13 and 14 formed or provided in the opposite sides of the gear casing 7.

Upon this drive shaft is fixedly mounted or keyed a worm 15 meshing with and driving a worm wheel 16 having its hub 17 pressed upon a bushing 18 adapted to rotate on the lower end of the agitator shaft. Above the worm wheel 16 is an eccentric 19 provided with an index plate 20 having one or more indexing holes or notches 21 for selectively coupling the worm wheel to the index plate and eccentric by means of a pin or

plunger 22 carried on a clutch 23. This clutch is slidably mounted on the projecting hub 17 of the worm wheel and is adapted to be raised and lowered by means of a bifurcated yoke 24 having arms or fingers 25 seating in an annular groove 26 formed in the periphery of the clutch. The 55

yoke is pivotally mounted adjacent its elbow in a clip plate 27, the vertical arm 28 of the yoke being pushed inwardly to lower the clutch 23 by means of a plunger 29 and disconnect the drive mechanism. This plunger is carried by an extension push rod 30 which in turn is connected to an oscillating rod 31 by means of a toggle mechanism 32. A handle 33 permits the vertical oscillating rod 31 to be moved to an "on" or "off" position. When the extension push rod is moved to an "off" position, it disengages the clutch 23, and when moved to an "on" position, the clutch is engaged and automatically coupled with the eccentric 19 by means of one or more springs 34, each forcing a plunger 35 against the lower surface of the clutch 23 and raising it into clutching or locking engagement, whereby the worm wheel 16 drives the eccentric 19 and index plate 20.

Mounted upon the eccentric 19 is a strap 36 having a connecting rod 37 pivotally connected at 38 to a whip-arm 39. This arcuate whip-arm 39 carries at its one end 40 a sleeve 40a pivotally mounted upon an eccentric hinge pin 41, and its swinging end 42 pivotally connected to a shuttle block 43 slidably mounted in the radially disposed guide of an arm 44, securely mounted on the agitator shaft 4.

The eccentric hinge pin 41 which, when swung from one dead center to the other, changes the position of the end 40 of the whip-arm 39 which in turn changes the relation of the swinging end 42 of the whip arm with the agitator shaft 4. Thus the closer the arcuate line of travel of this swinging end 42 comes to the center of the agitator shaft 4, the farther this shaft will oscillate, and the farther the arcuate line of travel of this swinging end 42 comes to the center of the shaft 4, the smaller arc will be traversed by the shaft 4 in its oscillating movement. Also it should be evident that the travel of the swinging arm 42 accelerates double; i. e., as the shuttle block 43 approaches the shortest radial length on the swinging arm 42, and at which time the eccentric hinge pin 41 passes through its greatest effective eccentricity. The same is true of the deceleration of the swinging arm and its associated parts; i. e., as the shuttle block 43 approaches the greatest radial distance on the swinging arm 42, the eccentric hinge pin 41 is nearing one of its dead centers.

It should be noted that the speed ratios between the eccentric hinge pin 41 and the agitator shaft 4 are constantly in parallel relation, whereby the agitator shaft will travel with greater accelerated and decelerated speeds and the agitator will impart this rapid change to the liquid and produce violent turbulence in the liquid with shorter strokes or arcuate travel than now is being accomplished with the more common eccentric or crank drive. It will be clearly apparent that with the increased whipping movements of the agitator or impeller 3, the latter need make shorter strokes or angular oscillations with the consequent result of a better circulation of the water and clothes carried thereby, and necessarily less tangling of the clothes.

In order to change the eccentricity of the hinge pin 41, the invention comprehends rotatably mounting the upper or outer reduced end 41a of this pin in the top plate of the housing 7 and connecting the outer squared end to a plate or bracket 45 adapted to be adjusted by means of a thumb or adjusting screw 46. Thus the operator may manually adjust and change the position of this eccentric hinge pin 41 by rotating the

bracket or plate 45 and thereby not only adjust the angle or arc of oscillation of the agitator drive shaft, but also adjust the speed of acceleration and deceleration of this drive shaft through its cycle of movement. An index plate *a* having suitable indentations or notches is adapted to receive the end of the adjusting screw.

In Fig. 4 there is disclosed an alternate construction in which the agitator shaft 4 is rotated in a long radial bearing 47 secured or pressed into the boss 48 of the gear housing 7. In this construction the clutch 49 which carries the plunger pin 22, is manually operated by a yoke 50 having opposite bifurcations or arms 51 seating in an annular race 52 in the clutch 49. Any suitable shifter arm may be provided for rotating the shaft 53 to raise or lower the clutch into or out of clutching engagement with the eccentric 19.

In order to drive the wringer shaft 54, the invention comprehends provision of a bevel gear 55 fixedly mounted on the hub 17 and under surface of the worm wheel 16. This bevel gear meshes with and drives a bevel gear 56 mounted upon a shaft 57 encased in the cylindrical housing or sleeve 58 and having at its opposite end a bevel gear 59 meshing with and driving a bevel gear 60 in the housing 61. This bevel gear 60 is mounted upon a stub shaft 62 suitably coupled at 63 to the wringer drive shaft 54. This housing 61 is provided with an offset projection 64 blended with and connected to a stub leg 65 suitably mounted upon the lower surface of the tub 2. The housing 61 is preferably made sectional and the sections suitably connected together by bolts or other suitable attaching means. The tub 2 is supported upon legs 66 and 67, the latter being carried by the wringer gear housing 61, while the motor or engine 8 is attached to and supported on a base frame 68 which suitably braces the legs and reinforces the structure.

In order to drain the washing fluid from the tub, the base of the tub is provided with an elbow 69 connected to the horizontal end 10 of a rigid L-shaped drain 71 having a vertical extension 72 and a discharge nozzle 73. Except when the tub is being drained, the extension 72 is maintained in vertical position by a collar 74 locked to the horizontal part 70 by a set screw 75, and a spring pressed plunger 76 carried by the collar. This plunger is adapted to normally engage in an indexing hole 77 in the stub leg 65, but may be withdrawn by means of a handle 78.

For the greater safety and to guard against the possibility of children tampering with the drain, the index plunger is located behind the leg in a less conspicuous location, but yet within easy reach of the operator. However, this same arrangement may be located at the front of the leg, if so desired.

From the above description and the disclosure in the drawings, it will become apparent that the invention comprehends a novel construction of power unit and drive mechanism for a washing machine and also for a wringer in which the drive mechanism for the washing machine may be readily and easily adjusted to change the angle or arc of oscillation and in which the agitator is given rapid, doubly accelerated and decelerated oscillatory movements to produce greater turbulence and gyratory flow of the washing liquid and further produce a more rapid turnover of the clothes to wash them with greater speed and efficiency, but with less danger of wear and tear.

Having thus disclosed the invention, I claim:

1. In a power unit for driving the agitator shaft of a washing machine, a drive member, an eccentric loosely mounted on the agitator shaft and adapted to be carried by the drive member and rotatable therewith, a connecting rod associated with the eccentric, a link connected to the rod intermediate its ends and fulcrumed at its one end with its other end connected to the agitator shaft to produce a rapid acceleration at the beginning of and deceleration at the end of each stroke. 5
2. In a power unit for operating the agitator shaft of a washing machine, a rotating member, an eccentrically mounted member for changing the rotation into an oscillatory motion, a link connected to said member and the agitator shaft for oscillating the agitator shaft with a substantially uniform acceleration and deceleration, and an adjustable mounting for one end of the link for varying the arc of oscillation and the rate of acceleration and deceleration of the agitator shaft. 10
3. In a power unit for driving the oscillating shaft of a washing machine, comprising rotating drive mechanism, means for changing the continuous rotation of the drive mechanism into an oscillatory movement, a link connected to said means and pivotally mounted at its one end and at its other end connected to the shaft for oscillating the shaft through a desired angle of oscillation and at a rapid rate of acceleration at the beginning of and deceleration at the end of each stroke, and means for adjusting the pivotal mounting of the link for varying the angle of oscillation and rate of acceleration and deceleration of the oscillating shaft. 15
4. In a power unit for driving the oscillating shaft of a washing machine, comprising rotating drive mechanism, means for changing the continuous rotation of the drive mechanism into an oscillatory movement, an arcuate link connected to said means and eccentrically mounted at its one end and its other end connected to the shaft for oscillating the shaft through a desired arc and cycle of oscillation, and means for varying the eccentricity of the mounting to vary the cycle of oscillation. 20
5. In a washing machine provided with an operating shaft, a power unit for driving the shaft comprising a continuously rotating drive means including a driven gear, eccentric means for changing the continuous rotation into an oscillatory movement, a clutch for connecting the drive and eccentric means, a link connected intermediate its ends to the eccentric means, one end of the link being eccentrically mounted, and a shuttle block connected to the other end of the link and to the oscillating shaft whereby the shaft is given a doubly accelerated and decelerated motion in its cycle of movement. 25
6. In a washing machine provided with an operating shaft, a power unit for driving the shaft comprising a continuously rotating drive means including a driven gear, eccentric means for changing the continuous rotation of the drive means into an oscillatory motion, a clutch carried on the driven gear and adapted to be moved into and out of clutching engagement with the eccentric means, an arcuate link connected to the eccentric means at a point intermediate the ends of the link, an eccentric mounting for one end of the link, a shuttle block connected to the opposite end of the link, an arm mounted on the operating shaft for oscillating the latter, and a guideway in the arm for slidably carrying the shuttle block. 30
7. In a washing machine provided with an operating shaft, a power unit for driving the shaft comprising a continuously rotating drive means including a driven gear, eccentric means for changing the continuous rotation of the drive means into an oscillatory motion, a clutch carried on the driven gear and adapted to be moved into and out of clutching engagement with the eccentric means, an arcuate link connected to the eccentric means at a point intermediate the ends of the link, an eccentric mounting for one end of the link, a shuttle block pivotally connected to the swinging end of the link, an arm mounted on the operating shaft for oscillating the latter, a guideway in the arm for slidably carrying the shuttle block, and means for varying the eccentricity of the end mounting of the link so as to vary the stroke and cycle of movement of the drive shaft. 35

JOHN MIKULASEK.
